CASING FOR A TEXTILE YARN BEAMING UNIT

John Cocker III, Gastonia, N.C., assignor to Cocker Machine and Foundry Company, Gastonia, N.C., a corporation of North Carolina

Filed Sept. 11, 1958, Ser. No. 52,610

Term of patent 14 years

(Cl. D55—1)

FIG. 1 —

FIG. 2 —

FIG. 3.

FIG. 4.

Fig. 1 is a perspective view of a casing for a textile yarn beaming unit embodying my new design;

Fig. 2 is a view in front elevation of the textile yarn beaming unit casing;

Fig. 3 is a view in plan of the textile yarn beaming unit casing; and

Fig. 4 is a view in side elevation of the textile yarn beaming unit casing.

The side not shown is substantially plain.

I claim:

The ornamental design for a casing for a textile yarn beaming unit, as shown and described.
